GOVERNOR

Albert Kalin, Cleveland, Ohio

Application April 1, 1942, Serial No. 437,122

15 Claims. (Cl. 121—42)

This invention relates to improvements in hydraulic relay governors of the type shown for example in my Patent 2,219,229, issued October 22, 1940, and in my application Serial No. 385,228 of March 26, 1941, now Patent No. 2,324,514, issued July 20, 1943. Without intention to limit the invention to governors of any particular class, the principles of the present invention will be discussed herein only as applied to speed governing. The principal objects are as follows:

One object is to provide an improved subservient control mechanism for a governor operating in part as a hydraulic relay.

Another object is to provide a hydraulic relay speed governor having a double-acting regulating servo-motor and a pilot valve controlling the same, wherein emergency control (e. g., shutting down or slowing down operation of the governed machine or apparatus) can be accomplished effectively through the agency of the governor without moving or disturbing the pilot valve; and, more specifically, wherein such emergency or similar control is accomplished by valving hydraulic regulating fluid at a point in the hydraulic system between the pilot valve and the servo-motor.

A further object is to provide an improved automatically operating emergency control mechanism for speed governors for prime movers, which control mechanism is responsive to special speed and load relationships—for example low speed and abnormally heavy load—for limiting power input to the prime mover under such condition (brake mean effective pressure control).

Another object is to provide an extremely sensitive speed responsive subservient control mechanism for a main speed responsive mechanism of a governor.

Another object is to provide an improved speed responsive, hydraulically operating subservient control mechanism for a hydraulic relay governor wherein adjustment for load limit and actuating speed point can be easily effected and maintained.

Other objects include the provision of an improved brake mean effective pressure control, hand shutdown and lubrication oil failure shutdown mechanism, in which the actuating parts are coaxially arranged but independently operable.

Still another object is to provide a hydraulically operable shutdown or slow down system for a hydraulic relay speed governor wherein all the essential parts can effectively be mounted on a unitary servo-motor block or body.

Referring to the accompanying drawing:

Fig. 1 is a general assembly schematic view of a speed governor incorporating the invention in one form;

Fig. 2 is a similar view, showing part only of the governor, with the principal valve elements hereof in a different relationship.

Referring to the main governor mechanism—shown at the left in Fig. 1, parts indicated generally by letters—A represents a positive displacement hydraulic pump, having a reversible valve system, adapted to draw hydraulic fluid from a sump S and deliver it to an accumulator B having a spring loaded plunger C and discharge vent D which cooperate to maintain pressure in a delivery duct E at substantially constant value. The pump A is suitably connected with the engine or other machine to be governed, as is also a speed responsive ballhead L of the governor.

Fluid from the accumulator is supplied continuously during operation of the governor through the duct E to a relatively small face F of a double acting regulating servo-motor piston G, tending to move said piston in a direction to decrease power input to the engine (downward movement as illustrated). Fluid from the duct E is controlled at a port E' of said duct by a lower land portion H' of a balanced pilot valve plunger H, so as to divert regulating hydraulic fluid from the duct E through a duct I, to the relatively larger face J of the servo-motor piston G. Certain special parts of the regulating fluid duct I will be more fully described later herein.

The pilot valve plunger is shown in neutral or balanced position; and when the piston is lowered from that position pressure fluid flows to said larger face of the piston G to cause power-input-increasing (upward) movement of said piston. Upward movement of the pilot valve plunger, from normal position, causes an upper land portion H'' of the plunger to open a port K leading to sump S thereby dumping fluid from below the servo-motor piston and causing power-input-decreasing movement of said piston by reason of the constant pressure maintained at the top face F of the piston.

The pilot valve plunger H is moved axially in opposite directions as a result of the difference between centrifugal force on flyballs L' of the ballhead and an opposing force exerted by an adjustable speeder spring M, so that an increase in speed on part of the engine (resulting from decrease in load) raises the pilot valve plunger and a decrease in speed (resulting from increase in load) lowers said plunger. An adjustable

speeder plug for the speeder spring is indicated at U.

Regulation in speed by the servo-motor incident to change in load is initiated by said movements of the pilot valve plunger referred to above and as more fully described in my said patent.

The governor shown is isochronous and, for stabilization, a hydraulically acting compensation system is provided comprising, as shown, a working equivalent of that described in said patent; namely: an actuating primary compensation pump N of the servo-motor acting through a compensation fluid duct O on a receiving primary compensation piston element P of the pilot valve plunger H, said piston P slidably sealing an end portion of the duct O opposite the pump. A coil spring Q corotatively connects the receiving compensation piston P and the pilot valve plunger (opposite ends of spring respectively threaded to portions of the piston and valve plunger) so that the piston is maintained in continuous rotation relative to its coaxial cylinder. Thereby the receiving compensation piston is always free from static friction and ready at all times to impart, through the spring, yielding restraining compensating influence axially on the pilot valve plunger during load change. Secondary compensation is secured by a restricted adjustable leak aperture (needle valve R) communicating the interior of the compensation fluid duct O with the governor sump and which acts to dissipate the force stored in the spring Q by each movement of the pump plunger N incident to movement of the servo-motor piston G.

In my Patent No. 2,324,514 there is shown and claimed a subservient control system including means for diverting high pressure hydraulic fluid from a part of the hydraulic governor relay to a hydraulic compensation system such as above described, whereby (as in certain emergencies) temporarily to take control of the engine away from the main speed weighing mechanism (the ball head L, etc.) by operating the main pilot valve independently of the speed weighing mechanism. Said arrangement operates very effectively in connection with a hydraulically double acting regulating servo-motor, that is: one which is fluid pressure operated both in "fuel on" and "fuel off" direction. Such a servo-motor in a hydraulic relay governor cannot be caused to move in the "fuel off" direction simply by venting hydraulic fluid from the appropriate end of the regulating servo-motor cylinder because the resultant decrease in speed of the flyball head would immediately cause hydraulic fluid to be vented also from the opposite end of the servo-motor cylinder and cause the "fuel off" movement to cease. However, said arrangement (per Patent No. 2,324,514) for certain practical uses required shutting off of the secondary compensation leak-off from that part of the hydraulic compensation system into which the high pressure fluid was diverted—as for shutdown purposes—thus sometimes complicating the construction and requiring disproportionate expense. The present arrangement, inter alia, simplifies the valving equipment necessary for making a positively acting hydraulic subservient control, such as that of said application Serial No. 385,228, when applied to governors having hydraulically double acting speed regulating servo-motors. The arrangement has other important advantages which will be pointed out later herein.

Referring further to Fig. 1, portions of the regulation fluid duct I which conveys hydraulic fluid

to and from the larger pressure space of the regulating servo-motor are formed or located in a unitary servo-motor block I attached rigidly to the power case 2 of the governor as along a smooth face indicated by the line 3. Said block is separable from the power case, as usual. A horizontal portion 4 of the duct I intercepts a vertical bore 5 leading downwardly from the top face of the servo-motor block. The lower end of the bore 5 intercepts a generally closed space 6 of the servo-motor block above and partially surrounding the smaller diameter trunk portion 7 of the power piston G, which space 6 is suitably vented to sump. Intermediately of the ends of the vertical bore 5 a horizontal portion 9 of the regulating fluid duct I extends from said vertical bore 5 and is connected with the relatively larger cylinder portion of the servo-motor as through a fixed tube 10 slidable in an axial bore of the piston G, which axial bore communicates with a lateral passage 11 in the piston leading to a point below the face J of the piston. Mounted in the vertical bore 5 for axial adjustment therein is a valve sleeve 15 having a cylindrical bore 16 extending therethrough and necked portions 17 and 18 forming separate cylindrical lands 19, 20 and 21 on the sleeve fitting the bore 5. The necked portion 17 has lateral ports 4' communicating the portion 4 of the duct I with the interior of the valve sleeve. The necked portion 18 has ports 9' communicating the portion 9 of the duct I with the interior of the valve sleeve. Slidable in the axial bore 16 of the valve sleeve 15 is a valve plunger 25 having a stem 23 and cylindrical lands 26 and 27 fitting the bore 16 and separated by a neck 28. The valve plunger lands 26 and 27 normally are spaced well above and below the ports 4' and 9' respectively of the valve sleeve for enabling free movement of fluid in the duct I from end to end thereof, whereby normally to permit the main pilot valve H to have full control of the regulating servo-motor at all times. Below the lowermost land (21) of the valve sleeve 15 is an additional set of lateral ports 24 which lead from the axial bore of the sleeve to sump space as will be obvious from the drawing.

The operating stem 23 of the valve plunger 25 extends upwardly out of the sleeve 15 for enabling the subservient control operations, mentioned earlier, by sliding of the valve plunger into different positions in respect to the ports of the sleeve 15. The valve plunger 25 is arranged to be adjusted automatically (for one operation hereof) by a low speed responsive ball-head mechanism indicated generally at 30, which mechanism will be described in detail presently.

For operation of the subservient control valve mechanism automatically in accordance with predetermined load and speed relationships (B. M. E. P. control, outlined above), the valve sleeve 15 is arranged to be shifted by the servo-motor piston G from an initial position, in which the low speed responsive mechanism of the valve plunger 25 never takes control away from the main pilot valve plunger, gradually into raised positions in which said mechanism of the valve plunger 25 can take control; but only in a manner to decrease or cut off fuel supply to the engine.

In the illustrated arrangement the lower end of the valve sleeve 25 extends into a position to be engaged by the upper face of the trunk portion 7 of the piston G during the upward travel of said piston during a minor portion of its stroke, e. g.: last 25% of "fuel on" movement.

A suitable spring 32 (shown at the upper end of the valve sleeve 15) urges the valve sleeve downwardly; and a vertically adjustable abutment 33, shown as screw threaded to the lower end of the valve sleeve 15, may be used to determine the point at which the servo-motor piston will commence to raise said valve sleeve. The abutment 33, for example, can be arranged for adjustment from a point outside the servo-motor block. 34 represents a screw (or toothed rack) meshing with vertical or nearly vertical flute teeth 35 on the abutment 33 by which the abutment may be turned to adjust it with reference to the valve sleeve. The teeth 35 are long enough to enable the necessary vertical movement of the valve sleeve without separation from the adjusting member 34.

For brake mean effective pressure control of internal combustion (e. g., Diesel) engines equipped with the present governor mechanism the ballhead 30 is mounted, as on the servo-motor block 1, in position to control the valve plunger 25 cooperatively with the movements of the valve sleeve 15 by the servo-motor. As shown, the ballhead 30 comprises a tubular body 40 mounted for rotation, as in antifriction bearing assemblies 41 and 42, on a bracket 43 supported by the servo-motor block. The ballhead body 40 has a driving pinion 44 keyed thereto, between the bearings; and the pinion is driven from a gear 45 on the main ballhead L, as through an idler gear 46 suitably supported in fixed position on some rigid part of the governor and in constant mesh with the gear 45 and driving pinion 44.

Flyballs 47 pivoted to the ballhead 30 have arms 48 bearing upwardly against a thrust plate (disc) 49 on the stem 23 of the valve plunger 25; and a coil spring 50 bears downwardly on the thrust plate and tends to hold the flyballs in their inward position (as shown in broken lines). The upper part of the ballhead is in the form of a rigid sleeve 40' encasing the spring 50 and having vertical slots 51 through which the ball arms 48 extend. The slots 51 of the sleeve 40' limit the outward movement of the flyballs, and the upper end of the sleeve is adapted to carry a tubular threaded adjusting plug 53 and locknut 54 by which the compression of the spring 50 may be easily adjusted and fixed at the necessary value.

Because it is frequently desirable to use the valve mechanism (valve plunger 25, etc.) for emergency shutdown purposes the stem 23 of the valve plunger 25 is so made at its upper end that it can readily be depressed by a force exerted otherwise than by the coil spring 50, while nevertheless enabled to rotate continuously within the coacting valve sleeve 15 whereby to prevent sticking and lack of sensitivity in responding to changes in speed imparted to the flyballs 47. As shown, the stem 23 of the valve plunger has an enlarged flange or shoulder element 55 fixed thereto which is held in contact with the under side of the thrust plate 49 by the spring 52 which is contained within the ballhead body 40. If the thrust plate 49 were to be fastened rigidly to the stem of the valve plunger (as it would be in a construction wherein no supplemental, e. g., hand, shutdown is required) then the spring 52 and shoulder element 55 would be omitted. The upper reduced end 57 of the valve plunger stem (part of shoulder element 55 as shown) slides in a central hole in the thrust plate 49, and

provision for making certain that the rotation of the thrust plate will also turn the valve plunger may comprise a splined connection between the reduced stem portion 57 and the thrust plate 49 as conventionally shown. The thrust plate is gripped at all times between the ball arms 48 and spring 50 and thereby caused to turn continually during operation of the governor, thereby continually spinning the valve plunger 25.

Lubrication oil failure shutdown

One emergency shutdown means in addition to the B. M. E. P. control ballhead mechanism 30 comprises, as shown, a pressure responsive motor in the form of a Sylphon bellows 60 suitably mounted in fixed position above the ballhead 30. The bellows is double walled, as shown, and one end of it carries a rigid thrust plate 61 adapted to operate a rod 62 extending loosely through the tubular adjusting plug 53 of the ballhead 30 to a point adjacent the upper end of the stem part 57 of the valve plunger 25. The rod 62 may have a rounded end which simply rests on the stem part 57 (also shown as rounded) for vertical support. If the bellows chamber is connected to an appropriate part of a forced feed lubrication system of the governed engine, and the pressure force in said system normally keeps the bellows distended beyond its normal length, then failure of lubrication oil pressure will cause the rod 62 to be lowered, depressing the valve plunger 25 a sufficient distance to cause shutting down of the engine in that event. An auxiliary collapsing spring 64 for the bellows 60 is shown above said bellows reacting, for example, against the usual cover plate of the governor speeder case (not shown).

Emergency hand shutdown

Another emergency shutdown means shown in Fig. 1 comprises an additional rod 67 having a lower end portion smaller than the rod 62 extending loosely through a central aperture 68 in the thrust plate 61 of the bellows and poised over the upper end of the bellows-actuated rod 62, so that the rod 62 and the valve plunger 25 may be operated downwardly at any time either by the bellows 60 or the rod 67. An operating button for the rod 67 is shown at 69. The button would ordinarily lie outside the top cover 70 of the governor so as always to be accessible for emergency shutdown of the engine by the attendant. The ultimate operation of the various mechanisms (30, 60, 67, etc.) through actuation of the valve plunger 25 will be reviewed later herein.

B. M. E. P. control operation

Assuming that the servo-motor piston G, as controlled by the main speed control ballhead mechanism L, is in the position illustrated, and that the engine is running at normal speed under full normal load, the flyballs 47 of the subservient control mechanism will then be in the position illustrated in full lines and the regulating fluid duct I will remain open from end to end. If the load on the engine is increased, causing the main ballhead L to decelerate, the main flyball mechanism will then cause the servo-motor piston to move upwardly or in the "fuel on" direction to enable the original speed of the engine to be reestablished notwithstanding the added load. But if the added load is of such magnitude that the engine speed drops until the centrifugal force on the subservient control flyballs 47 is insufficient to maintain the valve plunger 25 in

raised position then the upward regulation stroke of the piston will be limited, by operation of the valve plunger 25 and sleeve 15, to less than maximum "fuel on" travel, so long as excessive load continues to be imposed. Such operation of the subservient control mechanism can be made to limit the brake mean effective pressure in the engine cylinders to a safe value notwithstanding the fact that the normal operation of the main flyball mechanism L, through the pilot valve H, always operates to cause movement of the servo-motor piston G in the "fuel on" direction consequent upon deceleration of the engine.

Fig. 2 shows the relative position of the valve sleeve 15, valve plunger 25 and associated ports of the servo-motor block when the servo-motor piston G commences to lift the valve sleeve at a time when, because of low speed, the flyballs 47 swing inwardly and permit the spring 50 to lower the valve plunger 25 sufficiently to cut off the supply of regulating fluid to the servo-motor. Fig. 2 also shows the venting of regulating fluid from the lower part of the servo-motor cylinder to sump through the ports 24 past the land 27 of the valve plunger, so as to free the power piston G for downward movement by constant pressure applied at the smaller face F of the piston.

If the speed of the engine is abnormally slow when the trunk portion 7 of the servo-motor piston G raises the valve sleeve 15 (by engagement therewith near the end of the "fuel on" or upward stroke of the piston—see Fig. 2) then lowering of the valve plunger 25 by the slowly turning flyballs 47 will first seal the ports 4' (through operation of the plunger land 26) and then dump the operating fluid trapped in the right hand portion of the duct I to sump through the ports 24. Sealing of the ports 4' gradually stops the feeding of regulating fluid to the lower part of the servo-motor cylinder so that the main flyball head is prevented from causing further feeding of fuel to the engine; and unsealing of the ports 24 of the valve sleeve 15 at the upper edge of the land 27 of the valve plunger dumps the regulating fluid from below the piston G so that fluid from the duct E can then act against the upper face F of the piston G and commence to cause "fuel off" movement of said piston. Fluid will be fed to the upper side of the piston G notwithstanding the lowering of the main governor pilot valve H (as speed drops) because the supply portion of the regulation fluid duct I will be blocked at the closed ports 4' as shown by Fig. 2. The "fuel off" movement of the piston G will continue only until either the lowering of the valve sleeve 15 by the piston G or raising of the valve plunger 25 by the flyballs 47 unseals the ports 4' of the valve sleeve. Thus the feeding of fuel will be maintained at a safe maximum as determined by the setting of the abutment 33 (or the position of the lower end of the sleeve 15 in case there is no provision for adjustment) until either the excessive load is dissipated or normal speed resumed notwithstanding the abnormal load.

If the excessive load is dropped suddenly, the engine is nevertheless prevented from racing because, as soon as the engine speed increases toward normal, the flyballs 47 reposition the valve plunger 25 upwardly as from the position shown in Fig. 2 into a position closing the regulation fluid discharge ports 24 and opening the regulation fluid supply inlet ports 4', whereupon the main ballhead mechanism L, through the pilot valve plunger H and the speed stabilizing com-

pensation mechanism (N, P, etc.), immediately assumes control of the servo-motor piston G both in "fuel on" and "fuel off" direction to regulate the engine.

If for any reason the flyballs 47 do not become effective to raise the valve plunger 25 to a point such as will unseal the ports 4 (although closing the discharge ports 24 as in a neutral relative position of the valve plunger 25 and sleeve 15) in response to restoration of the engine speed upwardly toward normal, the fluid from below the piston G can nevertheless be vented as through a spring-closed check valve 72 located opposite the regulation fluid duct portion 9 and communicating the latter (for venting travel only of the fluid) with a portion of the duct I lying between the ports 4' and the pilot valve H. Thus at no time can fluid be trapped below the piston G to prevent the main ballhead mechanism from moving said piston in the "fuel off" direction.

In regard to the auxiliary shutdown mechanisms (60—62 and 67—69) it may be noted that those mechanisms can assume complete shutdown control of the engine at all times simply by enabling those mechanisms to depress the valve plunger 25 until the ports 4' are sealed by the valve plunger land 26 and the ports 24 are unsealed by movement of the upper edge of the plunger land 27 downwardly beyond the uppermost limits of said ports 24. Also it will be observed that the force necessary to be applied to the valve plunger 25 (as by the Sylphon 60) is wholly independent of any opposing action of the subservient control flyballs 47 (tending, particularly at high speed, to oppose downward movement of the valve plunger 25) because the valve plunger stem portion 57 can simply slide downwardly in the flyball thrust plate 49 as the shutdown actions of the Sylphon or hand operable rod 67 take place.

Load limit

Without substantial modification, the mechanism above described can be used to provide what is usually termed "load limit" governor operation—that is to say limiting of the extent of movement of the servo-motor in "fuel on" direction—Independently of speed. For illustration, there is shown an arm 75 adjustable as by turning a mounting shaft 76 for the arm to cause depression of the valve plunger 25 into a position in which the land 26 partly closes the ports 4' at normal speed. Then (as determined by the adjustment of the abutment 33 or its equivalent) the power piston G in raising the valve sleeve 15 near the end of the "fuel on" stroke will complete closing of the ports 4' and stop said "fuel on" movement of the power piston. The arm 75 may have paired arm elements arranged to bear on a shoulder 77 of the rod 62 when the arm 75 is turned a predetermined amount counterclockwise from the position in which shown. The operation of limiting the "fuel on" stroke of the servo-motor by means of the device 75—77 does not interfere with operation of the lube-oil failure shutdown mechanism 60—62 or of the hand shutdown rod 67; but said limiting operation could render the inward movement of the flyballs 47 inconsequential if the shoulder 77 were to be depressed by the arm 75 a sufficient amount so that said inward movement of the flyballs 47 would not cause abutment of the thrust plate 49 with the shoulder 55 of the valve stem as the flyballs 47 swing inwardly to their innermost position.

I claim:

1. In a hydraulic relay governor, comprising a pilot valve and a regulating servo-motor controlled by said valve and having differential pressure areas so arranged that pressure fluid maintained continuously at one pressure area causes regulating movement of the servo-motor in one direction upon pilot-valve-controlled relief of pressure at an opposed relatively larger pressure area of the servo-motor and pressure fluid applied at the effectively larger pressure area under control of the pilot valve causes regulating movement in an opposite direction, the combination therewith of a three port valve operatively interposed between the pilot valve and servo-motor and having plug means operable first to close a port leading to the pilot valve whereby to block fluid communication between the pilot valve and said effectively larger pressure area and then to open another port while the first port remains closed and a third port maintains communication between said three port valve and the effectively larger pressure area, whereby to vent pressure fluid from adjacent said latter area, and means for actuating said three port valve.

2. In a hydraulic relay governor, a regulating servo-motor and a pilot valve arranged to control a supply inlet and venting outlet duct for pressure fluid communicating with a pressure chamber of the servo-motor, whereby to condition the servo-motor for operation in opposite directions, valve means associated with said duct between the pilot valve and pressure chamber, said valve means having a plug element and cooperating port arranged to block the portion of the duct leading from the pilot valve to said valve means and another plug element and cooperating port arranged subsequently to vent the pressure chamber through the valve means and independently of the pilot valve while said first plug element remains in duct blocking position, means for actuating said valve means, and a one-way-acting relief-type valve in by-passing relation to the first mentioned plug element of said valve means for enabling venting of said pressure chamber by the pilot valve after the duct is blocked by the first plug element of the valve means and before the second plug element operates to effect venting of said pressure chamber.

3. In combination with a hydraulic relay speed governor comprising a main speed responsive means including a pilot valve and a regulating servo-motor controlled thereby; a subservient low-speed-responsive valve means acting on the hydraulic system in a manner temporarily to take control of the servo-motor away from the main speed responsive means, said subservient valve means including valve sleeve and valve plunger elements of circular section coacting for subservient valving operation, and rotary means connected with one of said elements and maintaining said elements continually in relative rotation.

4. In a hydraulic relay speed governor comprising a main speed responsive pilot valve mechanism and a regulating servo-motor controlled thereby and normally movable, a predetermined distance in opposite directions for "fuel on" and "fuel off" regulation, a subservient valve mechanism in a feed line of the servo-motor and operable to block passage of hydraulic fluid to the servo-motor, low speed responsive means controlling the valve in a manner tending to block said passage of fluid to the servo-motor, and

follow-up means connecting the servo-motor and subservient valve mechanism in a manner to cause completion of said blocking operation during a terminal portion only of the "fuel on" movement.

5. In combination with a hydraulic regulating servo-motor of a hydraulic relay speed governor having a main speed responsive pilot valve mechanism normally controlling said servo-motor; a 10) 15) 20) 25) 30) 35) 40) 45) 50) 55) 60) 65) 70) 75) 80) 85) 90) 95) 100) 105) 110) 115) 120) 125) 130) 135) 140) 145) 150) 155) 160) 165) 170) 175) 180) 185) 190) 195) 200) 205) 210) 215) 220) 225) 230) 235) 240) 245) 250) 255) 260) 265) 270) 275) 280) 285) 290) 295) 300) 305) 310) 315) 320) 325) 330) 335) 340) 345) 350) 355) 360) 365) 370) 375) 380) 385) 390) 395) 400) 405) 410) 415) 420) 425) 430) 435) 440) 445) 450) 455) 460) 465) 470) 475) 480) 485) 490) 495) 500) 505) 510) 515) 520) 525) 530) 535) 540) 545) 550) 555) 560) 565) 570) 575) 580) 585) 590) 595) 600) 605) 610) 615) 620) 625) 630) 635) 640) 645) 650) 655) 660) 665) 670) 675) 680) 685) 690) 695) 700) 705) 710) 715) 720) 725) 730) 735) 740) 745) 750) 755) 760) 765) 770) 775) 780) 785) 790) 795) 800) 805) 810) 815) 820) 825) 830) 835) 840) 845) 850) 855) 860) 865) 870) 875) 880) 885) 890) 895) 900) 905) 910) 915) 920) 925) 930) 935) 940) 945) 950) 955) 960) 965) 970) 975) 980) 985) 990) 995) 1000) 1005) 1010) 1015) 1020) 1025) 1030) 1035) 1040) 1045) 1050) 1055) 1060) 1065) 1070) 1075) 1080) 1085) 1090) 1095) 1100) 1105) 1110) 1115) 1120) 1125) 1130) 1135) 1140) 1145) 1150) 1155) 1160) 1165) 1170) 1175) 1180) 1185) 1190) 1195) responsive pilot valve mechanism, a hydraulic regulating servo-motor controlled by said mechanism, a subservient control valve including a valve plunger arranged in the hydraulic system of the servo-motor and adapted to be moved axially for subservient control of the servo-motor, a low-speed-responsive ballhead mechanism having flyballs operatively connected with the valve plunger, and a rod axially aligned with the valve plunger and supported independently of the ballhead for operating the valve plunger independently of the ballhead mechanism.

11. In a hydraulic relay speed governor, speed responsive valve mechanism and a regulating servo-motor controlled thereby, a subservient valve mechanism including a valve plunger also arranged to control the servo-motor at times, a low-speed-responsive ballhead mechanism connected to the valve plunger and including flyballs having a thrust plate resiliently maintained in operating abutting contact with a rigid portion of the valve plunger, a sliding connection between said rigid portion of the valve plunger and the thrust plate, and a rod aligned with said rigid portion for operation of the valve plunger independently of the position of the flyballs and thrust plate.

12. Mechanism according to claim 11, wherein pressure operated means connected with the rod normally prevents the rod from actuating the valve plunger, and spring means operates the rod axially upon failure or partial failure of pressure in said means.

13. In a hydraulic relay speed governor, speed responsive control valve means and a hydraulic speed regulating servo-motor controlled thereby, a valve including a valve plunger operatively associated with the governor for performing a subservient controlling operation on the servo-motor, a rod arranged for operating the valve plunger, a bellows in fixed position on the governor and having an apertured thrust plate for abutment with the rod adjacent the aperture

to operate said valve plunger in accordance with fluid pressure change in the bellows, and an additional rod movably mounted on the governor in alignment with the aperture in the thrust plate for operating the first mentioned rod without moving the thrust plate.

14. In a hydraulic relay speed governor, speed responsive control valve means and a hydraulic speed regulating servo-motor controlled thereby, a valve including a valve plunger operatively associated with the governor and arranged for performing subservient control operations on the servo-motor, said plunger having an operating stem, low-speed-responsive means having an operating connection with the valve plunger stem, a remotely controllable motor and a rod connected therewith and aligned with said stem for operating the latter by the motor, and a hand operable rod aligned with the first mentioned rod for operating the valve plunger independently of the low-speed-responsive means and motor.

15. In a hydraulic relay speed governor for prime movers, speed responsive valve mechanism and a speed regulating servo-motor controlled thereby, a subservient valve mechanism including a valve plunger also arranged to control the servo-motor at times, a ported valve sleeve operable with the valve plunger and arranged to be shifted by operation of the servo-motor during part of a regulating stroke thereof in power-input increasing direction, yielding means normally maintaining the valve plunger in an inactive position with respect to a port of the sleeve, and an adjustable load limit device operatively associated with the valve plunger and capable of moving the valve plunger into positions rendering the movement of the valve sleeve effective to cause cessation of movement of the servo-motor in said power-input-increasing direction.

ALBERT KALIN.
